UNITED STATES PATENT OFFICE.

DUSTIN KEMBLE, OF LISBON, OHIO.

ROLLING-CHAIR.

1,262,806.

Specification of Letters Patent. Patented Apr. 16, 1918.

Application filed July 3, 1915, Serial No. 37,943. Renewed May 11, 1917. Serial No. 168,044.

To all whom it may concern:

Be it known that I, DUSTIN KEMBLE, a citizen of the United States, residing at Lisbon, in the county of Columbiana and State of Ohio, have invented certain new and useful Improvements in Rolling-Chairs, of which the following is a specification.

My invention relates particularly to electrically propelled invalid or pleasure chairs and their control and has for its object the provision of a safe, comfortable and useful vehicle which can be readily operated and controlled by invalids, delicate persons or others both for convenience and pleasure. To attain this object, and advantages which will be herein described, I employ the construction and operating and controlling means shown in the accompanying drawings in which:

Figure 1 is a plan and Fig. 2 is a side elevation of a chair embodying my invention.

Fig. 3 is a plan view in partial section on a horizontal plane through the main wheels and axle of the chair, the section being taken on line *a*—*b* of Fig. 4.

Fig. 4 is a vertical section on line *c*—*d* of Fig. 3.

Fig. 5 is a partial section on an enlarged scale through the motor shafts, on line *c*—*d* of Fig. 3.

Fig. 6 is a longitudinal section through the hub of one of the main wheels of the chair.

Fig. 7 is a transverse section of the main wheel driving ratchet on line *e*—*f* of Fig. 6.

Fig. 8 is a section on line *g*—*h* of Fig. 3 showing the arrangement of springs and other details.

Fig. 9 is a diagram of the electrical connections and controlling devices which I employ.

Fig. 10 is a partial section on line *x*—*x* of Fig. 4, showing the location of the operating and brake levers.

Fig. 11 is a fragmentary view showing the brake and its connections.

Referring to the drawings, 1, represents the chair or vehicle body which is provided with a seat, 2, the back, 3, the floor plate, 4, the panel, 5, the steering post bearing, 6. Any suitable upholstery, 7, may be employed. The chair is provided with two main ground or driving wheels, 8, 9, whose functions will be presently described.

12 is the main wheel axle. The major portion of the weight of the chair body, the

equipment and the passenger is carried by the underslung springs, 13, 14, whose ends are connected to the seat, 2, by the spring shackles, 15, 16. The springs, 13, 14, are connected to the under side of the bearings, 17, 17, in which the axle, 12, revolves, by means of the spring bolts, 18, 18.

The main wheels, 8, 9, are rotatively mounted upon the axle, 12. In Fig. 6 the details of the main wheel hub construction are shown. 19 is the body of the hub which, as shown, is provided with flanges, 20, 20, to which are secured the inner ends of the wire spokes, 21, 21. 22 is the bearing bushing for the axle, 12, in the wheel hub, 19. 23 is a brake drum formed upon, or which may be attached to the wheel hub. 24 is a brake band which, by means of suitable connections, such as lever, 25, and rod, 26, Fig. 11, may be made to tighten about the drum, 23, and retard or stop the chair. The outer end of the wheel hub, 19, is extended in the form of a cylindrical flange, 27, on the inner surface of which is formed a ratchet, 28. Co-operating with this ratchet is the pawl, 29, which is pivoted to the collar, 30, which is keyed to the axle, 12, and secured thereto by means of the washer, 31, and nut, 32. Shoulders, 33 and 34, are formed upon axle, 12, the distance between these shoulders being slightly greater than the length of the bushing, 22, so that when collar, 30, is clamped tightly against shoulder, 34, the hub, 19, may still be free to rotate.

It will be seen that as the axle, 12, is rotated in the direction to propel the chair forward, the pawl, 29, will engage a tooth of the ratchet, 28, and cause the main drive wheel to rotate and carry the chair with it. I prefer to provide this ratchet and pawl drive for each of the main drive wheels, although it is not absolutely essential to the operation of the chair. One of the main drive wheels may be fixed to the axle with a permanent driving connection and the other may be journaled on the axle to run free in either direction. Or, the ratchet and pawl of one wheel may be arranged to propel the chair forward and those of the other wheel be arranged to propel the chair backward upon reversal of the motor. With my preferred arrangement, however, a very satisfactory compensating movement takes place between the wheels when turning corners, and it is not essential that the chair be power driven for backing.

The main drive wheels, 8, 9, are shown provided with hand rims, 35, 36, which may be used for manipulating the chair as desired.

5 Upon the outer end of the drive wheel hub, 19, is screwed the hub cap, 37. A spring, 38, of any convenient form may be used to force the pawl, 29, into engagement with the teeth of the ratchet, 28.

10 The steering wheel, 10, is carried by the fork, 39, the stem of which swivels in the steering post bearing, 6. A hand steering lever, 40, connected to the stem of the fork, 39, in the manner common to bicycle and tri-cycle construction, is provided.

15 To the axle, 12, is keyed or otherwise secured by an operative connection, the worm wheel, 41, which is adapted to be driven by the motor, 42, by means of the clutch, 43, 20 and worm, 44. Attached to bearings, 17, 17, by bolts, 18, 18, and supported on axle, 12, by bearings, 45, 46, is the frame or plate, 47, upon which is mounted the housing, 48, which incloses worm wheel, 41, and worm, 25 44. Annular bearings, 49, 50, carried by housing, 48, take the radial thrust, and thrust bearings, 51, 52, take the end thrust of worm, 44. The frame or plate, 47, has longitudinal arms, 53, 54, extending parallel 30 with axle, 12, and cross arms, 55, 56, extending crosswise to the axle, 12. The longitudinal arms, 53, 54, are secured to the under side of bearings, 17, 17, by the bolts, 18, 18, which also serve to secure the springs, 13, 14, 35 as previously described.

To the under side of cross arm, 55, is secured the direct current motor, 42, whose armature shaft, 57, is extended through the hub of worm, 44, and is free to revolve therein. One member, 58, of jaw clutch, 43, is mounted upon and keyed to an extension of the hub of worm, 44, and the other member, 59, of clutch, 43, is slidably mounted upon shaft, 57, and driven thereby through the 40 key, 60. The outer end of shaft, 57, projects beyond the hub of worm, 44, and has one member, 61, of a jaw clutch, 62, keyed to it. The other member, 63, of clutch, 62, is slidably mounted upon the rotor shaft, 64, of another motor, 65, which is secured to the under side of cross arm, 56, of plate, 47, the two shafts, 57 and 64, being in axial alignment. A key, 66, makes driving connection between shaft, 64, and clutch member, 63. 45 A sleeve, 67, surrounds the adjacent ends of shafts, 57 and 64, and enters counterbores in clutch members, 61 and 63, to assist in preserving the alignment of these shafts, which are free to revolve in sleeve, 67.

50 It will be seen from the foregoing description that motion may be imparted to worm, 44, from shaft, 57, when clutch, 43, is engaged, and that motion may be imparted to shaft, 57, from shaft, 64, when clutch, 62, is 55 engaged. It will also be obvious that when

clutch, 62, is disengaged, worm, 44, may be driven by motor, 42, through clutch, 43, while motor, 65, is at rest.

The object of the above described arrangement of parts is to provide for propelling 70 the chair by motor, 42, by current from the storage battery, 68, which is carried by a supporting frame, 69, supported by attachments to the body of the chair, and to further provide for disengaging the motor, 42, 75 from the chair propelling mechanism and for driving this motor, 42, as a generator for charging the storage battery, by power developed in motor, 65, which may be either of the direct or alternating current type, and 80 which is adapted to be connected to an external source of electric current.

At the rear of the vehicle, I provide a swivel wheel, 11, carried by a fork, 70, the stem of which, 71, is supported in a bearing in frame, 72, which is divided and extends forward to the axle, 12, to which it is 85 rotatively secured by bearings, 73, 74.

Cross arm, 55, has an extension, 75, which projects beyond the motor, 42, and is provided with a guide, 76, for a vertical pin, 77, which is pivotally secured at 78 to frame, 72. Surrounding pin, 77, between the extension, 75, of cross arm, 55, and frame, 72, is a helical spring, 79, pressing, at the top, against 90 the extension, 75, and at the bottom, against the frame, 72, with any initial tension that may be found necessary or desirable.

The objects of the rear wheel, 11, and 95 spring, 79, are to prevent the backward overturning of the chair and to provide a means for cushioning certain shocks which would otherwise be directly and suddenly imparted to the chair body, through the main springs, when the vehicle runs over an obstacle, particularly when mounting or descending a street curbstone. A further object of the wheel, 11, is to provide means for resisting the tendency of the worm, 44, to travel 100 around the worm wheel, 41, when power is being transmitted from the motor, 42, to the axle, 12. This tendency is resisted in part by designing the chair so that its center of gravity, when the chair is completely equipped, is in front of the axle, 12, and is 105 further resisted by the reaction of the roadway upon the wheel, 11, which is transmitted through the wheel fork, 70, frame, 72, and spring, 79, to plate, 47, to which is secured the housing 48, which supports the bearings 110 for the worm.

115 It will be seen that the above mentioned tendency of the worm, 44, to travel around the worm wheel, 41, is met only by spring resistance. The moment of the weight of the chair resists the moment of the worm about the axle, 12, through the main springs, 13, 14, to whose axle bearing supports, 17, 17, the worm housing, 48, is rigidly connected by plate, 47; and the moment of the 120

125 130

roadway reaction upon wheel, 11, acts through the spring, 79, as previously described. These are important features of my invention which add materially to the comfort of the passenger and to the mechanical life of the chair.

Particular attention is drawn to the organization and functions of my rear wheel whose objects have already been briefly outlined. By my construction, it is possible for the chair to be driven over obstacles without fear of physical discomfort of the passenger. When mounting a curb, the passenger, by leaning back in the chair may partially relieve the front wheel of its pressure on the roadway and place a considerable weight upon the rear wheel, so that the front wheel will readily mount the curb. Then, by leaning forward, the total weight of the chair and passenger may be largely divided between the front and rear wheels, so that the main drive wheels will readily mount the curb, when the rear wheel will follow without imparting severe shock to the passenger. Similarly, when descending a curb, the wheels may be dropped in succession from front to rear, with a minimum of discomfort to the passenger.

While I have shown only one front and one rear wheel, it will be obvious to those skilled in the art that two wheels may be used instead of one, either in front or in the rear, or both in front and rear, and that they may be connected to their supports in any well known manner. For the sake of lightness and simplicity, I prefer to use only one front and one rear wheel.

The electrical connections and control of my chair are shown in diagram in Fig. 9. In this figure the electric motors, switches, and other devices are shown in conventional symbolism. In this diagram, 42 is the chair propelling motor, and 65 is the motor which is employed for driving motor, 42, as a generator for charging the storage battery, 68. 80 is a rheostat for use in starting and operating motor, 42. The operation of the rheostat is effected by means of lever, 80^a, and suitable mechanical connections shown by dotted lines in Fig. 10. 81 and 82 are circuit controlling switches adapted to perform certain functions which will be presently described.

81 is a single pole switch, adapted to be manually opened, the arm, 83, of which is pivoted at 84 to a contact electrically connected to one terminal of the storage battery, 68. A spring, 85, is provided to close arm, 83, upon contact, 86, which is electrically connected to brush, 87, of motor, 42. The arm, 83, is provided with a notch or other means for engaging with a detent hook, 88, upon the lever, 89, which carries the keeper, 90, of electromagnet, 91. A spring, 92, attached to lever, 89, opposes the

pull of electromagnet, 91, and is adapted to hold detent hook, 88, in engagement with the notch in arm, 83, to hold the latter in open position shown by full lines in the drawing. 93 is a stop pin for limiting the movement 70 of lever, 89. 94 and 95 are stop pins for limiting the movement of switch arm, 83.

82 is a three pole switch, having switch arms, 96, 97 and 98, pivoted respectively to contacts, 99, 100 and 101. The three 75 arms, 96, 97 and 98, are mechanically connected by the cross bar, 102. Switch, 82, is adapted to be manually closed, and to be opened by the action of a spring, 103, which is shown attached to an extension of arm, 80 96, beyond the pivot contact, 99. The extension of arm, 96, is provided with a notch or other means for engaging with a detent hook, 104, upon the lever, 105, which carries the keeper, 106, of electromagnet, 107. A 85 spring, 108, attached to lever, 105, opposes the pull of electromagnet, 107, and is adapted to disengage the detent hook, 104, from the notch in the extension of arm, 96, and permit the switch, 82, to be opened by 90 spring, 103. The arms, 96, 97 and 98, of switch, 82, make contact with terminals, 109, 110 and 111 respectively, when thrown to the right, as shown in the drawing. An additional terminal, 112, is provided, and 95 arm, 98, makes contact with this terminal when the switch, 82, is thrown to the left. Stop pins, 113 and 114, are provided to limit the movement of the arms of switch, 82. Switches, 81 and 82, may be located 100 at any convenient place on the chair.

The connections and functions of the devices just described will be best understood from the following description of the electrical operation and control of my invention.

Assuming that the battery is properly charged and that the chair is ready for operation, the position of the switches will be as follows:—Rheostat, 80, will be open, its contact lever being thrown to the left as shown in the drawing. Switch, 81, will be closed, as shown by the dotted lines in the drawing. Switch, 82, will be thrown to the left, opening the circuits through arms, 96 and 97, and closing arm, 98, upon terminal, 112. Before starting the chair, the clutch, 62, will be disengaged and clutch, 43, will be engaged. To start the chair, the passenger will move the lever of rheostat, 80, to the right, closing the circuit through the rheostat. As soon as the rheostat circuit is closed, current will flow from the battery, 68, through the motor, 42, by way of the following circuit:—From terminal, 115 120 115, current will flow through conductor, 116, rheostat, 80, conductor, 117, motor, 42, conductor 118, switch, 81 and conductor, 119, to the other terminal, 120, of battery, 68. It will be seen that switch arm, 83, is 130

shunted by electromagnet, 91, the circuit being made from the terminal, 86, through conductor, 120^a, electromagnet, 91, conductor, 121, switch arm, 98, and conductor, 122, to terminal, 84. The coil of electromagnet, 91, is, however, of fine wire, or, in other words is a voltage coil, and the current which will flow through it when switch arm, 83, is closed, will be negligible.

- 10 It will be seen that the chair may be operated by merely manipulating the lever of the rheostat, 80. Should it occur that the switch, 81, has been left open, it will be automatically closed as soon as the circuit is 15 made through rheostat, 80. For, under such conditions, the potential of the battery will be applied to the coil of electromagnet, 91, at terminals, 86 and 84, and the detent hook, 88, will be disengaged by the pull of electromagnet, 91, thus allowing switch, 81, to close and the motor, 42, to start.

To charge the battery by current developed in the motor, 42, driven as a generator by motor, 65, clutch, 43, is disengaged and 25 clutch, 62, is engaged. Connections are made to an external source of electric current, by any suitable means to terminals, 123 and 124, of the circuit leading to the motor, 65. Switch, 81, is manually opened 30 and is retained in an open position by detent hook, 88. Switch, 82, is now manually thrown to the right and held there until detent hook, 104, engages to retain the switch closed. The closing of switch, 82, 35 completes the circuit through motor, 65, by way of terminal, 123, conductor, 125, motor brushes, 126 and 127, conductor, 128, switch arm, 97, conductor, 129, and terminal 124. It will be seen that up to this time the 40 battery circuit to motor, 42, is open. As soon as the motor, 65, starts to rotate, an electro-motive force will be generated in the armature of motor, 42, which now becomes a generator. A circuit from dynamo, 42, through 45 electromagnet, 91, is completed when switch arm, 98, contacts with terminal, 111, the circuit passing from brush, 87, through conductor, 118, terminal, 86, conductor, 120, electromagnet, 91, conductor, 121, arm, 98, 50 conductor, 130, and conductor, 117, back to the dynamo, 42. The strengths of electromagnet, 91, and spring, 92, are so proportioned that the pull of the electromagnet, 91, will overpower that of the spring, 92, 55 upon lever, 89, when the electro-motive force of dynamo, 42, is sufficient to overcome that of the battery, 68. When such a condition is reached, detent hook, 88, will release switch arm, 83, and the latter will be thrown 60 into contact with terminal, 86, by spring, 85.

A circuit will now be established from the dynamo, 42, through battery, 68, from brush, 87, through conductor, 118, switch arm, 83, conductor, 119, battery, 68, conductor, 116, 65 conductor, 132, electromagnet, 107, switch

arm, 96, conductor, 131, and conductor, 117, back to the dynamo, 42. As soon as the battery charging current energizes electromagnet, 107, sufficiently to overpower the spring, 108, the lever, 105, will be pulled upward 70 and detent hook, 104, will engage the notch on the extension of arm, 96, and hold the switch, 82, closed as shown in the drawing, and the hand of the operator may be removed.

Should the current decrease so that the pull of spring, 108, overpowers that of the electromagnet, 107, the detent hook, 104, will again be disengaged from the notch on the extension of switch arm, 96, and switch, 80 82, will be opened by spring, 103, thus stopping motor, 65, and opening the circuit between the battery, 68, and dynamo, 42.

For handling the chair up and down stairs, as, for instance, when taking the chair 85 into a house or onto a porch, I provide a drum, 133, and cable, 134. The drum, 133, is rotatively and slidably mounted upon axle, 12, and is provided with a friction clutch element, 135, on one side adjacent to 90 the hub of worm wheel, 41, which carries a corresponding friction clutch element, 136. A lever, 137, pivoted at 138 to the plate, 47, and in operative engagement with the drum, 133, is provided for shifting the latter so 95 that its clutch element, 135, will engage the clutch element, 136, on worm, 41.

In order to operate this drum and cable device to draw the chair up an incline, I provide a reversing switch, not shown, for 100 the motor, 42. When equipped with this device, both of the main drive wheels, 8, 9, are provided with ratchet drives for forward propulsion only, and the rotation of the axle, 12, in the reverse direction is not 105 transmitted to the drive wheels. The cable, 134, is, accordingly, placed upon the drum, 133, so as to wind upon it, when axle, 12, is rotated in the reverse direction.

Upon the frame of the chair body, upon 110 or near the steering post bearing, 6, I provide a guide, 139, for the cable, 134.

When it is desired to haul the chair up stairs or other steep incline, the cable, 134, is brought forward through guide, 139, and 115 attached to a suitable fixed anchor or post, the motor, 42, is reversed and the clutch members, 135 and 136, engaged. The cable, 134, will now be wound upon the drum, 133, and the chair will be drawn up the incline. 120

To let the chair down an incline, the cable, 134, is attached as before to the fixed anchor or post, and the chair is let down the incline by allowing the clutch members, 135 and 136, to slip by manipulating the lever, 137. If 125 the inclination of the teeth of the worm wheel, 41, and worm, 44, is such that motion cannot be transmitted from the worm wheel, 41, to the worm, 44, it will not be necessary to operate the motor, 42, when letting the 130

chair down an incline. If motion can be transmitted from worm wheel, 41, to worm, 44, the motor, 42, will be operated in the direction to wind cable, 134, on drum, 133, and the descent of the chair will be controlled by the friction of clutch members, 135 and 136, as before.

To prevent the rotation of the drum, 133, when not in use I provide projections upon its hub which will engage corresponding projections upon bearings, 46. I prefer to arrange these interlocking projections so that they will not engage immediately upon the release of clutch members, 135 and 136, but so that there will be an intermediate position in which the drum may rotate freely when the cable is being paid out for attachment to the fixed point.

It will be apparent that the chair may be drawn up an incline, backward, or let down an incline forward, by running the cable to the rear of the chair instead of to the front.

To assist in the support of the chair body, and to prevent undue vibrations of it, I provide the slotted post guides, 140, 141, which permit the chair body and axle to have free, vertical, relative movement but prevent the direct forward and back movement which is objectionable to nervous persons.

It will be seen from the foregoing that I have provided simple and safe, yet complete method and means for the control and operation of my electrically propelled invalid chair, self contained in the organization of the chair and equipment. The advantages of my invention are numerous and not found in any similar apparatus which has been proposed, so far as I am aware.

Some of these advantages are:

The chair, having both front and rear wheels, can not be overturned forward or backward. This feature gives the passenger a sense of security and a positive protection which the ordinary rolling chair does not afford.

Forward and back vibrations, or jiggling, which are very trying to the nerves, are almost entirely eliminated or are transformed into a spring cushioned swaying, by my improved construction, the chair body being at all times pivoted on the main axle by the slotted post guides so that movements of the chair body relative to the main axle are confined to vertical or rotary movements.

By my construction the width of the chair may be made so that it may be used on narrow sidewalks and pass through crowds with a minimum of inconvenience.

An especial advantage of my invention lies in its ability to negotiate street crossings as has been previously mentioned.

No garage or special housing provision is needed for my chair as it may be kept in the house or any building and readily handles itself in entering and leaving.

No special facilities are needed for charging the electric storage battery as such facilities are provided by my invention.

No pushing attendant is necessary, yet the chair has the ability to ascend and descend steeper grades than it would be possible for either man pushed or hand rim propelled chairs to negotiate with safety if at all.

Its weight is small compared to that of the smallest automobile.

Further, and perhaps most important, the use of my invention adds greatly to the privilege, independence and enjoyment of life by delicate persons, of which they are otherwise, for the most part deprived.

Having thus described my invention, I claim and desire to secure by Letters Patent:

1. In a rolling chair, the main drive wheels, the axle therefor, the steering wheel, the chair body, springs for the chair body supported by bearings upon the axle, a plate fixed to the bearings and extending rearwardly therefrom, a frame swiveled on the axle and extending rearwardly therefrom, a rear wheel mounted in a support carried by the frame, and a spring interposed between the plate and the frame to oppose the backward overturning of the bearings about the axle.

2. In a rolling chair, the main drive wheels, the axle therefor, the steering wheel, the chair body, springs for the chair body supported by bearings upon the axle, a plate fixed to the bearings and extending rearwardly therefrom, a motor mounted on the plate and having a driving connection with the axle, a frame swiveled on the axle and extending rearwardly therefrom, a rear wheel mounted in a support carried by the frame, a spring interposed between the plate and the frame to oppose the backward overturning of the bearings about the axle, and driving means between the axle and the main drive wheels.

3. In a rolling chair, main drive wheels mounted upon an axle, spring supports carried by the axle, a chair body, springs interposed between the chair body and said spring supports, a frame swiveled upon the axle and extending rearwardly therefrom, a ground wheel mounted in said frame, and means interposed between said frame and said spring supports to oppose the backward overturning of the spring supports.

4. In a rolling chair having an axle and two ground wheels loosely mounted upon the axle, a drum carried by the axle, a cable wound upon the drum and adapted to have its free end secured to a fixed point at a distance from the chair, means carried by the chair for preventing the rotation of the axle, and a friction brake between the axle and the drum to control the rotation of the drum when lowering the chair by gravity.

5. In a rolling chair, drive wheels mounted upon an axle, two independent frames swiveled on said axle, a chair body mounted on one of said frames, a rear ground wheel mounted on a support in the other of said frames, and elastic means interposed between said frames, whereby, when said ground wheel is supported upon the ground, said elastic means opposes the backward overturning about said axle of the frame on which said chair body is mounted. 70

10. In a rolling chair, a pair of drive wheels rotatably mounted on an axle, means coöperating with the axle and one of the drive wheels whereby said wheel is rotated by said axle for propelling the chair forward, a housing supported by bearings rotatably mounted on the axle, a chair body, springs mounted on said housing and connected to the chair body to form a support therefor, a frame pivoted to rock in a vertical plane transverse to said axle, a rear ground wheel carried by said frame, a motor carried by said housing, driving connections between said motor and said axle, a steering wheel connected to the front of the chair body adapted to support a portion of the weight of the chair, and a spring interposed between said housing and said frame to oppose the backward overturning of said housing about said axle. 75

15. In a rolling chair, drive wheels mounted upon an axle, a main frame carried by bearings upon said axle, a chair body supported by springs upon said frame, a second frame pivoted to rock in the same vertical, longitudinal plane as said main frame, and having one end extending rearwardly from said axle, a rear ground wheel carried by a support in said second frame, and a spring interposed between said frames to resist the backward overturning of said main frame about said axle. 80

20. In a rolling chair, drive wheels mounted upon an axle, two independent frames carried by said axle extending rearwardly therefrom one above the other and adapted to rock to and from each other about said axle, a chair body carried by the upper said frame, a ground wheel carried by the lower said frame, and a spring interposed between said frames to yieldingly hold them apart. 85

25. In a rolling chair, drive wheels mounted upon an axle, two independent frames carried by said axle extending rearwardly therefrom one above the other and adapted to rock to and from each other about said axle, a chair body carried by the upper said frame, a ground wheel carried by the lower said frame, and a spring interposed between said frames to yieldingly hold them apart. 90

30. In a rolling chair having drive wheels and an axle therefor in driving connection with one of said wheels, a worm wheel mounted upon the axle in driving connection therewith, a housing for said worm wheel swiveled on said axle, a worm mounted in bearings in said housing and operatively engaging said worm wheel, a motor mounted on said housing, driving connections between said motor and said worm, a chair body supported on said housing, a frame pivoted to rock about said axle and extending rearwardly therefrom, a rear ground wheel carried by a support in said frame, and a spring interposed between said housing and said frame to oppose the backward overturning of said housing about said axle. 95

35. In a rolling chair having drive wheels and an axle therefor in driving connection with one of said wheels, a worm wheel mounted upon the axle in driving connection therewith, a housing for said worm wheel swiveled on said axle, a worm mounted in bearings in said housing and operatively engaging said worm wheel, a motor mounted on said housing, driving connections between said motor and said worm, a chair body supported on said housing, a frame pivoted to rock about said axle and extending rearwardly therefrom, a rear ground wheel carried by a support in said frame, and a spring interposed between said housing and said frame to oppose the backward overturning of said housing about said axle. 100

40. In a rolling chair having drive wheels and an axle therefor in driving connection with one of said wheels, a worm wheel mounted upon the axle in driving connection therewith, a housing for said worm wheel swiveled on said axle, a worm mounted in bearings in said housing and operatively engaging said worm wheel, a motor mounted on said housing, driving connections between said motor and said worm, a chair body supported on said housing, a frame pivoted to rock about said axle and extending rearwardly therefrom, a rear ground wheel carried by a support in said frame, and a spring interposed between said housing and said frame to oppose the backward overturning of said housing about said axle. 105

45. In a rolling chair having drive wheels and an axle therefor in driving connection with one of said wheels, a worm wheel mounted upon the axle in driving connection therewith, a housing for said worm wheel swiveled on said axle, a worm mounted in bearings in said housing and operatively engaging said worm wheel, a motor mounted on said housing, driving connections between said motor and said worm, a chair body supported on said housing, a frame pivoted to rock about said axle and extending rearwardly therefrom, a rear ground wheel carried by a support in said frame, and a spring interposed between said housing and said frame to oppose the backward overturning of said housing about said axle. 110

50. In a rolling chair having drive wheels, and an axle therefor in driving connection with one of said wheels; power transmitting gearing connected to said axle; a housing for said gearing supported by bearings on said axle; a motor mounted on said housing; driving connections between said motor and said power transmitting gearing; a chair body supported on said housing; a frame, pivoted to rock in a vertical plane transverse to said axle, extending rearwardly therefrom; a rear ground wheel carried by a support in said frame; and a spring interposed between said housing and said frame to oppose the backward overturning of said housing about said axle. 115

55. In a rolling chair having drive wheels, and an axle therefor in driving connection with one of said wheels; power transmitting gearing connected to said axle; a housing for said gearing supported by bearings on said axle; a motor mounted on said housing; driving connections between said motor and said power transmitting gearing; a chair body supported on said housing; a frame, pivoted to rock in a vertical plane transverse to said axle, extending rearwardly therefrom; a rear ground wheel carried by a support in said frame; and a spring interposed between said housing and said frame to oppose the backward overturning of said housing about said axle. 120

60. In a rolling chair having drive wheels, and an axle therefor in driving connection with one of said wheels; power transmitting gearing connected to said axle; a housing for said gearing supported by bearings on said axle; a motor mounted on said housing; driving connections between said motor and said power transmitting gearing; a chair body supported on said housing; a frame, pivoted to rock in a vertical plane transverse to said axle, extending rearwardly therefrom; a rear ground wheel carried by a support in said frame; and a spring interposed between said housing and said frame to oppose the backward overturning of said housing about said axle. 125

65. In a rolling chair having drive wheels, and an axle therefor in driving connection with one of said wheels; power transmitting gearing connected to said axle; a housing for said gearing supported by bearings on said axle; a motor mounted on said housing; driving connections between said motor and said power transmitting gearing; a chair body supported on said housing; a frame, pivoted to rock in a vertical plane transverse to said axle, extending rearwardly therefrom; a rear ground wheel carried by a support in said frame; and a spring interposed between said housing and said frame to oppose the backward overturning of said housing about said axle. 130

14. In a rolling chair, an axle; ground wheels rotatably mounted thereon; a drum rotatably mounted on the axle; a cable wound upon the drum and adapted to have its free end secured to a fixed point at a distance from the chair; a motor mounted on the chair; irreversible driving connections between the motor and the axle; means for engaging and disengaging said motor and said driving connections; friction means between said axle and said drum; and means for engaging and disengaging said friction means; whereby, when said axle is rotated by said motor, said drum may be rotated to wind said cable, and whereby when said cable is secured to a fixed point at a distance from the chair the movement of the chair down an incline may be controlled by said friction means.
15. In a rolling chair, an axle; ground wheels rotatably mounted thereon; a drum rotatably mounted on the axle; a cable wound upon the drum and adapted to have its free end secured to a fixed point at a distance from the chair; locking means on said chair independent of said axle adapted when engaged with said drum to lock it against rotation; and means for engaging said drum and said locking means.
16. In a rolling chair, an axle; ground wheels rotatably mounted thereon; a drum rotatably mounted on the axle; a cable wound upon the drum and adapted to have its free end secured to a fixed point at a distance from the chair; a motor mounted on the chair; driving connections between the motor and the axle; friction driving means between the axle and the drum; means for engaging and disengaging said friction means; locking means on the chair, independent of the axle, adapted, when engaged with said drum, to lock it against rotation; and means for engaging said drum and said locking means.
17. In a rolling chair, a pair of main carrying wheels mounted on an axle; a front steering wheel; a chair body spring supported on said axle; a swivel support for said steering wheel fixed to said chair body; a rear ground wheel; and means for holding said rear ground wheel in vertically yielding contact with the ground so that a portion of the weight of the chair is at all times carried by said rear ground wheel.
18. In a rolling chair, a pair of main carrying wheels and an axle therefor; a chair body extending forward and backward from said axle; spring supports interposed between the axle and the chair body; a steering wheel mounted by a fork and swivel joint support upon the chair body in front of the axle; and a ground wheel at the rear of the axle, mounted by a fork and swivel joint support yieldingly connected to the chair body; whereby both the front steering wheel and the rear ground wheel are each made to carry a part of the weight of the chair at the same time on uneven as well as on even ground.
19. In a rolling chair, a pair of main carrying wheels and an axle therefor; a chair body; supporting means connecting the chair body and the axle; a steering wheel mounted by a fork and swivel joint support at the front of the chair; a rear wheel and elastic means for holding said rear wheel in yielding contact with the ground, said elastic means reacting through the chair body upon said steering wheel to cause said steering wheel and said rear wheel to carry part of the weight of the chair at the same time on uneven as well as on even ground.
20. In a rolling chair, a pair of main carrying wheels and an axle therefor; a chair body mounted by springs on said axle; a front steering wheel mounted in a fixed swivel support at the front of said chair and a rear wheel mounted in a swivel support at the rear of the chair; said swivel support for the rear wheel having a yielding spring connection with the chair body whereby said chair body may be tilted backward so as to raise said steering wheel above the level of the ground with which the other wheels of the chair are in contact, in order to facilitate the mounting of a street curb or other obstacle.
21. In a rolling chair, a pair of main carrying wheels and an axle therefor; a chair body mounted on said axle; a front steering wheel mounted in a swivel support at the front of said chair; a rear ground wheel mounted in a swivel support at the rear of the chair; and elastic means interposed between said rear wheel support and the chair body whereby said rear wheel is yieldingly pressed against the ground to cause said rear wheel and said steering wheel to carry part of the weight of the chair at the same time on uneven as well as on even ground.
22. In a rolling chair, a pair of main carrying wheels and an axle therefor; a chair body; springs connected by shackles to the chair body and supported by bearings on said axle; a front steering wheel carried by a swivel support at the front of the chair body; a rear ground wheel and a support therefor; and elastic means interposed between said rear ground wheel support and said bearings for holding said rear ground wheel in resiliently yielding contact with the ground, thus forming a compound lever of said chair body and said springs whereby the weight of the chair is carried partly by the main carrying wheels.
23. In a rolling chair, a pair of main carrying wheels and an axle therefor; a chair body spring mounted upon said axle;

a steering wheel connected to the chair body in front of the axle, a swivel mounting carrying a ground wheel at the rear of the axle and having an elastic connection to 5 the chair body adapted to press said ground wheel against the ground below as well as in or above the plane of contact of the other wheels with the ground, thus causing both the steering wheel and the ground wheel 10 to carry part of the weight of the chair at all times on uneven as well as on even ground.

24. In a rolling chair, a pair of main carrying wheels and an axle therefor; a 15 chair body and springs interposed between the axle and the chair body; a steering wheel carried by a swivel support at the front of the chair and a rear ground wheel carried by a swivel support having a 20 resilient connection to the chair body; and a post connected to the bottom of the chair body extending downward therefrom, and provided with a vertical slot to receive said axle as a guide therefor, and thus to prevent

forward and backward vibration of said 25 chair body and torsional strains of said springs.

25. In a rolling chair, a pair of main carrying wheels and an axle therefor; a 30 chair body and springs interposed between the axle and the chair body; a steering wheel carried by a swivel support at the front of the chair and a rear ground wheel carried by a swivel support having a resilient connection to the chair body; and a 35 post on either side of the chair connected to the chair body, extending downward therefrom, each post being provided with a vertical slot to receive and to form a guide for said axle, and thus to prevent torsional 40 and side strains on said springs.

In testimony whereof I affix my signature in presence of two witnesses.

DUSTIN KEMBLE.
